IDLE DAGGER ROD AND LIGHT SHUTTLE
BOX DEVICEJames Chapman, Atlanta, and Benjamin W.
Brown, Hapeville, Ga.

Application August 22, 1935, Serial No. 37,338

5 Claims. (Cl. 139—347)

Our invention relates to improvements in the protector mechanism of looms. The invention has for its particular object the reduction in the movement of such parts of known types of looms as the dagger, or daggers, the protector rod, and parts associated therewith. It is also an object of our invention to reduce to a minimum the motion of any of the parts associated with the so-called smash protection mechanism and to make such parts of this mechanism as are subjected to continual motion as light, simple, and free running, as possible. It is also an object of our invention to reduce the heavy pressure now imposed upon a shuttle, whenever it leaves or enters either box, thereby giving what is known as a free box. Our invention eliminates all motion of the dagger or daggers and of the protector rod and associated parts except during the period when a stoppage is about to occur. It will be obvious that in a loom where the daggers and protector rod may oscillate as many as 10,000 times an hour that any device which will entirely stop the motion of these parts, which are not only very heavy but which must of necessity carry an extremely heavy spring load, will materially reduce the power required to run the loom and will also reduce the wear and tear on the machine as a whole and will especially reduce the wear on such parts as the shuttles, belts, picker-sticks, pickers, lug straps, lug sticks, pick-balls, and hangers. It will appear as the description proceeds that when our invention is installed on a loom that the taper commonly present in the shuttle boxes may be materially reduced, if not entirely eliminated, thereby increasing the bearing surface on the shuttle from about 20% as is now usual practice to as much as 100% in some cases. As a result of this increase in bearing surface as well as the light spring pressure on the shuttle it will be seen that there will be much less danger of crushing or otherwise distorting the shuttle while it is in the box.

Prior to our invention the protector rod, daggers, and parts associated therewith oscillated with every beat of the loom, this motion was interrupted only when a shuttle failed to be properly boxed in which case the dagger or daggers were not lifted into the clearing position and as a result struck the steels in the frogs which knocked off the shipper handle and stopped the loom. According to our invention the dagger or daggers are held in a stationary position during the entire time that the loom is operating in a normal manner, (i. e. so long as the shuttle fails to enter either box) but should the shuttle fail

to be properly boxed then, according to our invention, the dagger or daggers will be positively moved into the position of protection so as to strike the steels in the frogs, thereby knocking off the shipper handle and stopping the loom. 5

In the accompanying drawing which is made a part hereof only those portions of a loom are shown which are necessary to properly illustrate our invention. Throughout the drawing similar parts will be referred to by similar characters 10 of reference.

Fig. 1 is a plan view of the loading lever which is an important unit of our invention.

Fig. 2 is a side view of the loading lever referred to in Fig. 1 showing in this case a modified form of linkage attachment, and also showing the lever in its extreme lower position against the stop. 15

Fig. 3 is a side view of a modified form of the protector rod control lever.

Fig. 4 is a side elevation of a conventional loom showing the preferred form of our invention installed thereon; in this view the lay is shown in its extreme forward position.

Fig. 5 is a side elevation of a conventional form 25 of loom showing our invention installed thereon; in this view the lay is shown in a position such that the pitman is in a partially raised position.

Fig. 6 is a rear view showing part of a conventional loom with our invention installed thereon. 30

Fig. 7 is an enlarged view of the stop mechanism which forms a part of the loading lever used in our invention.

Fig. 8 is an end view of the fixed portion of 35 this mechanism.

Fig. 9 is an end view of the stop shoulders on the movable portion of this mechanism.

Fig. 10 is a plan view showing one form of upper bearing pin and the method of attaching it to the pitman. 40

Fig. 11 is an end view of this fitting showing the pitman, to which it is attached, in section.

Fig. 12 is a plan view of the loading lever (10) shown in Figs. 1, 2, 4, 5, 6, and 7, showing in 45 this case a spring (75) for holding this lever against its lower stop.

In the drawing which forms a part of this application our invention is shown in place on a conventional loom, however, only such portions of 50 this loom are shown as will enable those skilled in the art to understand the construction and operation of the invention. Throughout this drawing the numeral 1 refers to the main frame of the loom, 2 refers to the lay, 3 to the swords, 55

4 to the daggers, 5 to the protector rod, 6 to the pitman, 7 to the shuttle box, 8 to the shuttle, and 9 to the shuttle box finger. In our invention a special form of lever 10 which is referred to as a loading lever throughout these specifications, is shown mounted on a rod or pin 11 extending out from the side of the loom frame 1. This lever is supplied with a plurality of notches 12 on which a weight 13 can be hung. If desired a plurality of holes could be drilled through the side of this lever and the weight 13 could be hooked therein in any suitable manner, or for that matter, the weight 13 could be dispensed with entirely and a spring 75, Fig. 12 could be 15 used in its place. Attached to the loading lever 10 at or near its end are two bearing pins 14 and 15. These pins can be disposed opposite each other as shown in Fig. 1 or displaced from each other as shown in Fig. 2, or for that matter may 20 be located in any suitable manner with respect to the lever so long as the desired results can be obtained. In the preferred form of the invention shown in Figs. 4, 5, and 6, a rod 16 with a suitable boss or bearing formed on its lower end is fitted 25 on the bearing pin 15 and a second rod 17 with an elongated yoke 18 at its lower end is fitted on the bearing pin 14. The rod 16 has a yoke 19 formed at its upper end which is in every way similar to the yoke 18 formed on the lower end 30 of the rod 17. The yoke 19 on the rod 16 is fitted over a special bearing pin 20 which is mounted on the pitman in any suitable location. The upper end of the rod 17 is fitted with a clevis 21 or other suitable fitting which is attached to the 35 protector rod control lever 22 in any suitable manner. The operation of the device is substantially as follows. Before installing the invention on a conventional form of loom it is first necessary to reverse the direction of the protector rod 40 spring 23 so that it will serve to hold the protector rod 5 against its upper stops thereby holding the daggers 4 normally in their extreme upper position. This change in the sense of action of the protector rod spring 23 is an important 45 feature of our invention since it causes the daggers 4 to stay stationary against their upper stops and in a position substantially perpendicular to the plane which contains the lay and the swords as long as the loom is operated in a normal 50 manner. It will be apparent as the description proceeds that the daggers will have no motion with respect to the lay except when a smash is about to occur, in this respect the action of the daggers on a loom upon which our invention has 55 been installed is entirely different from their action on a loom which is not equipped with our device since on such a loom the daggers normally oscillate with every beat of the lay. At the same time that the protector spring 23 is reversed it is 60 loosened to a material degree since with our invention the protector spring serves the primary purpose of holding the daggers against their upper stops while in a loom not equipped with our invention this spring must be very tight so that 65 it can force the heavy daggers down into the stopping position in a fraction of a second and at every beat of the loom. It will be obvious that with the conventional arrangement the shuttles must at every stroke be forced into their boxes 70 against this heavy spring load thus causing them to undergo excessive wear and also consume large amounts of power which could otherwise be used to operate the loom or other machinery. With our device installed on the loom substantially 75 as shown in the drawing and with the protector

rod spring reversed in direction and lightened in action as just noted the loom will function in the following manner. When the lay is in its forward position the shuttle 8 will normally be in its box 7, thus forming a firm support against 5 which the shuttle box finger 9 can press. Under these conditions the protector rod and the daggers attached thereto cannot be rotated so as to allow the daggers to drop. It will be seen by referring to Fig. 4 that the rod 17 which is 10 attached at its upper end to the protector rod control lever 22 is in tension under this condition and serves to support the loading lever 10 against the action of the spring (75) or the weight (13) as the case may be. As the lay beats back 15 the shuttle leaves the box but the protector rod and its attached daggers are now prevented from rotating by the action of the rod 16 and its associated fittings since the raised position of the pitman causes this rod to pick up the load of the 20 lever 10 and the weight or spring attached thereto. The front rod 17 is now relieved of its load as will be seen by reference to Fig. 5 wherein the yoke 18 attached to the lower end of this rod is shown clear of its bearing pin 14. As the lay 25 moves still further to the rear the pitman 6 starts to lower and the rod 16 begins to assume a lower position such that the loading lever will rotate in a downward direction. If this action were allowed to continue the load would be transferred 30 back to the front rod 17 before the shuttle was in its box thus causing the weight 13 to pull down the protector rod control lever 22 and cause the protector rod 5 to rotate in such a manner as to depress the daggers which is not desired. In 35 order to prevent such a condition from occurring the loading lever 10 is formed with a shoulder 24 which is so disposed that in certain positions it will rest against a shoulder 25 which is attached rigidly to the loom frame 1 by means of the pin 40 11 upon which the loading lever 10 rotates. The shoulders 24 and 25 are so disposed that when the loading lever drops below a certain point it will be supported entirely by the shoulders 24 and 25 thus relieving the rods 16 and 17 of its weight. 45 As the lay continues to beat forward the front rod 17 will also move forward and will again pick up the weight 13. However, it should be noted that before the load is transferred from the shoulders 24 and 25 to the rod 17 that the 50 shuttle will be in its box and the tension in the rod 17 cannot depress the daggers. It will thus be seen that the shuttle actually enters a free box but immediately it enters the box and before it has any time to jump or bound out that the 55 weight 13 or the spring (75) is, through its associated connections, caused to bear against the shuttle and thus hold it in place. It will also be seen that just before the shuttle starts to leave the box that the lever 16 picks up this load, thus 60 allowing the box to become free and allowing the shuttle to be expelled therefrom with a very light force. It will likewise be obvious to all those skilled in the art that should the shuttle for any reason fail to enter the box at the proper 65 time that the rod 17 will, due to the action of the weight 13 or the spring (75), pull down on the protector rod control lever, thus rotating the protector rod 5 which will in turn depress the daggers 4, thereby causing them to strike the steels in the 70 frogs 26 and stop the loom. When the device is properly installed and adjusted the action is very smooth and the load is transferred from the lever 17 to the lever 16, thence to the shoulders 24 and 25 and thence back to the lever 17 without caus- 75

ing the daggers to move or oscillate in the slightest degree and without causing a shock or blow to come on the system. During this whole cycle the shuttles will never enter or leave a box or move therein except when the yoke 18 is in its free position as illustrated in Fig. 5 thus giving at all times, when the shuttle is in motion, a free box. It will be obvious to all those skilled in the art that either or both of the yokes 18 and/or 19 could be dispensed with and other suitable fittings which would perform the same function could be used. In Fig. 3 one such modified arrangement is shown. In this case the protector rod control lever 22 is simply fitted with a hole of diameter considerably larger than the diameter of the front rod 17 and this rod which now has a stop 27 at its upper end is allowed to slide therein. In a similar manner the back rod 16 could be suitably modified and attached to a specially drilled fitting attached to the pitman, or for that matter the lower ends of either or both rods could be allowed to slide in fittings of this character attached to the loading lever. It will likewise be obvious that both of the yokes 25 could be fastened to either the upper or the lower ends of the rods and such a form of construction is illustrated in Fig. 2 wherein the lower bearing pins 14 and 15 are shown displaced with respect to each other. In this figure the loading lever 30 is shown in its extreme low position resting against the stops 24 and 25. If it is desired to dispense with rigid rods such as 16 and 17 any form of suitable tension members such as rope, cable leather or steel straps could be used and 35 the yoke fittings 18 and 19 could be entirely eliminated since with this form of construction the members referred to would simply flex whenever they were out of action thereby allowing the machine to operate substantially as described. 40 As a matter of fact the machine will operate in a satisfactory manner with the back rod 16 entirely removed but in this case during certain portions of the stroke the dagger will oscillate slightly which is not desired. It should be borne 45 in mind however that one rod operation is entirely suitable since a relatively free box is obtained and the oscillation of the dagger is much less than that which occurs in the conventional form of loom, while at the same time all of the 50 safety features of the device are retained.

Having thus described our invention what we claim as new is:

1. A loom with a shuttle, a shuttle box, a binder, a binder finger, and means for stopping the loom, 55 a protector rod and a dagger attached thereto mounted on the lay of the loom, spring means associated with said protector rod and so disposed as to hold said dagger in its upper position, an arm mounted on said protector rod, a lever 60 pivotally mounted on the frame of the loom, rod means connecting said lever to said arm, a pitman, and rod means connecting said pitman to said lever, load means for depressing said lever and stop means associated with said lever and the 65 frame of the loom, the combination of means being so disposed that when the shuttle of the loom is in its box that the lever, and its associated load, is supported by means of the rod connected to the arm aforementioned, the protector rod, 70 the binder finger, the shuttle binder, and the shuttle, but when the shuttle is not in its box and the pitman is in a raised position, the lever, and its associated load is supported by the rod connected to the pitman and the pitman, and when 75 the pitman is in a depressed position the lever,

and its associated load, is supported by the stops attached to said lever and to the frame of the loom, in all cases the protector rod and the daggers associated therewith being free of load and held against their upper stops by means of the 5 spring aforementioned unless the lay should be forward and the shuttle out of its box in which condition the lever, and its associated load, acts through the rod and the protector arm aforementioned and causes the protector rod to rotate 10 against the action of the protector rod spring thus throwing the daggers into engagement with the stopping means thereby stopping the loom and preventing a smash.

2. A loom with a lay, a shuttle, a shuttle box, 15 and a protector rod mounted on the lay, a dagger attached to said protector rod and loom stopping means adapted to cooperate with said dagger, a lever pivotally mounted on the frame of the loom, stop means for preventing an extreme 20 downward movement of said lever, spring means attached to said lever and tending to force it against said stop means, means associated with said protector rod and said lever such that in case a shuttle of the loom should fail to be properly boxed that said lever will be depressed in the direction of the stop means aforementioned thereby rotating the protector rod in such a way as to throw the daggers attached thereto in a 25 position where they will strike the loom stopping 30 means thus stopping the loom.

3. A loom with a shuttle and a shuttle box, a lay and a pitman adapted to actuate said lay, a protector rod mounted on said lay and a protector rod spring adapted to actuate said protector rod, daggers attached to said protector rod and adapted to rotate therewith, an extension arm attached to said protector rod and adapted to rotate therewith, a loading lever and means connecting said extension arm to said loading 40 lever pivotally mounted on the frame of the loom, means connecting the pitman to said loading lever and adapted to oscillate said loading lever, and stops to limit the movement of said loading lever, spring means associated with said loading lever 45 and so disposed with respect thereto as to urge it in the direction of said stops and in a direction opposed to that caused by the means attached to the pitman, means adapted to transfer the load of said spring means directly to the shuttle 50 whenever the shuttle is in its box, said means being so disposed, however, that should the shuttle fail to be properly boxed the spring load aforementioned will act through the extension arm, 55 attached to the protector rod, and cause said protector rod to rotate the daggers, attached thereto, into the position for protection.

4. A loom with a shuttle and a shuttle box, a lay and a pitman adapted to actuate said lay, a protector rod mounted on said lay, daggers attached to said protector rod and adapted to rotate therewith, an extension arm attached to said protector rod and adapted to rotate therewith, a loading lever pivotally mounted on the frame of the loom, means connecting said extension arm to the loading lever, means connecting the pitman to said loading lever and adapted to oscillate said loading lever, and stops to limit the movement of said loading lever and means including the loading lever, and the protector rod extension arm, aforementioned, adapted to rotate the protector rod and the daggers attached thereto into the position of protection in case the shuttle should fail to be properly boxed.

5. A loom with a shuttle, a shuttle box, a binder, 75

- a binder finger, and means for stopping the lay, a protector rod and a dagger attached thereto mounted on the lay of the loom, spring means associated with said protector rod and so disposed as to hold said dagger in its upper position, an arm mounted on said protector rod, a lever pivotally mounted on the frame of the loom, means connecting said lever to said arm, a pitman, and means connecting said pitman to said lever, load means for depressing said lever and stop means associated with said lever and the frame of the loom, the combination of means being so disposed that when the shuttle is in its box that the lever, and its associated load, is supported by the means connected to the arm, aforementioned, the protector rod, the binder finger, the shuttle binder,

and the shuttle, but when the shuttle is not in its box and the pitman is in a raised position, the lever, and its associated load is supported by the means connected to the pitman and the pitman, and when the pitman is in a depressed position, 5 the lever and its associated load are supported by the stops attached to said lever and to the frame of the loom, the combination of means being so disposed, however, that should the shuttle fail to be properly boxed, the lever and its associated 10 load will cause a rotation of the protector rod and the dagger attached thereto in a direction such as to cause the dagger to engage the lay stopping means and stop the lay.
